UNITED STATES PATENT OFFICE.

JOSEPH SAVOIE, OF CENTRAL FALLS, RHODE ISLAND, ASSIGNOR OF ONE-HALF TO
EDWARD C. GLINES, OF PROVIDENCE, RHODE ISLAND.

TEMPLE-BOW HOLDER FOR FRAMELESS SPECTACLES.

988,666.

Specification of Letters Patent.

Patented Apr. 4, 1911.

Application filed February 19, 1910. Serial No. 544,779.

To all whom it may concern:

Be it known that I, JOSEPH SAVOIE, a subject of the King of Great Britain, residing at Central Falls, in the county of Providence and State of Rhode Island, have invented certain new and useful Improvements in Temple-Bow Holders for Frameless Spectacles, of which the following is a specification.

10 In United States Letters Patents granted to me March 16, 1909, and June 29, 1909, and numbered 915,487 and 926,293, respectively, I have represented and described certain improvements in frameless spectacles.

15 My present invention also relates to spectacles of the frameless or rimless type and it consists essentially in the novel construction of the connection or temple-bow holder member itself, and in means for removably 20 securing it to the nose-piece and temple-bow, all as hereinafter set forth and claimed.

In my said patented improvements the inner end portion of the temple-holders or bent wire connections are adapted to be secured or attached to nose-pieces specially devised to receive them. As thus constructed, the cost of production is materially increased; or, in other words, the temple-holders were not adapted to be rigidly secured 30 or even removably secured to ordinary nose-pieces, such as are usually carried in stock by opticians and dealers in optical goods.

The object of my present invention is to produce a temple-holder or connection member of the general type or character disclosed in said patents; the improved connection, however, being devised and constructed so as to be easily, quickly and firmly attached or fixed to the usual or ordinary 40 nose-piece, and also capable of being as readily disconnected from it. As thus devised, the cost of producing the connection is comparatively small, while the cost and time consumed in attaching it to the nose-piece is practically *nil*.

Another object of the present invention is to produce a more efficient and stronger joint device or pivot at the point where the temple-bow is attached to the outer or free

end of the temple-holder, while at the same 50 time permitting the temple-bow member to swing through a partial or complete circle, and also being readily disconnectible from it.

By means of my improvement herewith frameless spectacles as usually constructed, 55 that is, spectacles having the temple-bows jointed to the lenses, may be quickly and cheaply converted into spectacles having, when in use, the general appearance of frameless eye-glasses. That is to say, the 60 temple-bow members will then be jointed to bent wire holders having enlarged head portions superimposed upon and conforming to the back faces of the rear straps or ears of the well-known nose-pieces as devised for frameless spectacles, all the members being secured together by means of the usual fastening screw. As thus arranged, the said holders are inconspicuous when 65 viewed from the front of the lenses because 70 each holder is adapted to lie closely to the back of the lens and follow its semicircumference.

In the accompanying sheet of drawings, Figure 1 represents, in elevation, a pair of frameless spectacles embodying my improvement, viewed from the back of the lenses, portions of the temple-bows being omitted. Fig. 2 is a corresponding side elevation, in greatly enlarged scale, of one of the connections or temple-bow holders detached. Fig. 3 is a corresponding end view, viewed from the left of Fig. 2. Fig. 4 is an enlarged horizontal sectional view, taken on line 4 4 of Fig. 1. Fig. 5 is a vertical transverse 85 section, taken on line 5 5 of Figs. 1 and 4; and Figs. 6 and 7 are similar sectional views, taken respectively on lines 6 6 and 7 7 of Fig. 1.

The following is a detailed description of 90 the present invention and the co-operating parts:

It may be stated in advance that the construction of the lenses *l*, as well as the bridge or nose-piece *B* connecting them, is or may be the same as commonly employed 95 in frameless or rimless spectacles, except that the holes usually drilled in the outer

ends of the lenses for attaching the temple-bow joints thereto are omitted. The said nose-piece B, or lens holder, comprises the arch or bridge part proper, b , terminating at each end in a shank part b^1 and a pair of laterally separated perforated straps or ears b^2 , adapted to receive the lens l . The inner end of the latter is also engaged by the oppositely disposed curved vertical members d integral with the nose-piece. The lens is adapted to fill the space between the ears and to be detachably secured to them by a screw s , all as usually constructed. The said ear members are usually made plano-convex cross-sectionally, the outer face or surface being more or less curved or convex.

In producing my improved connection or one-piece temple-bow holder A, a short bar of gold or other suitable stock is first subjected, say to the action of a "combination" die, which reduces the stock to the elongated body or shank part a and the enlarged head portion a^1 . This latter constitutes the inner end part of the holder member and is preferably shaped so as to conform to the said convex or outer face of the ear of the nose-piece. The head part is made quite thin and, when in use, practically envelops or covers the corresponding portion of the ear, a hole s^1 registering with holes formed in the ears, is pierced through the stock and adapted to receive the usual retaining screw s ; the latter serving both to secure the lens to the ears of the nose-piece and for detachably securing the temple-bow holder itself to it. As thus devised the outer edge f of the head part a^1 is adapted to abut the adjacent face of the shank b^1 , although not interlocking with it. The wall of the head is quite thin, as before stated, thereby rendering it somewhat elastic, and resilient. When it is applied to or superimposed upon the ear member, its circumscribing rear edge f^1 may not engage the lens' surface, but is adapted to be in direct engagement with the corresponding part of the ear. I prefer to form the normal convexity of the head so as to produce a slight space or chamber c between it and the adjacent surface of the ear, thereby adapting it to produce a degree of tension between it and the screw s , thus securing the member A with greater efficiency and preventing it from becoming accidentally loosened. It may be further added that usually the inner faces of the elongated laterally separated straps or ears b^2 of a nose-piece are flat and adapted to bear directly against the respective faces of the lens, the outer faces of the ears having a somewhat convex form cross-sectionally, a single central screw s passing through the ears and lens serving to clamp all together. By shaping the rear face of the head part a^1 of the holder so as to practically fit the said convexity of the ear, the holder, when secured to the latter by the

central screw, is not only maintained in position transversely or sidewise but is held or locked against angular or swinging movement by reason of the coengaging convex and concave surfaces of the ear and head portions, respectively.

The outer or free end of the connection A is screw-threaded, as indicated at a^2 , thereby adapting it to be readily screwed into the tapped eye end o^1 of the temple-bow o . The latter, it may be observed, is or may be made as usually employed in spectacles, except that its joint end o^1 is enlarged and tapped, as just stated, to receive the said screw-threaded end a^2 of the member A.

I prefer to make the body part a of the temple-holder concentric or parallel with the semi-circumference of the outer edge of the lens l and disposed at the back of and contiguous to it. The outer end portion of the holder is bent or offset at a^3 (see Fig. 7) to permit the enlarged, ball-shaped end o^1 of the tapped temple-bow to swing freely thereon, as in opening and closing them.

It is obvious that, if desired, the members A may be readily disposed or positioned at the upper edge of the lenses without any change whatever in their construction. In such case, the relation of the holders to each other and to the lenses would be reversed; that is, the lower left holder, shown in Fig. 1, would then become an upper right one, and the lower right holder an upper left one.

What I claim as my present invention and desire to secure by United States Patent is:—

1. The improved one-piece temple-bow holder member herein described, comprising a curved shank or body part having one end constructed for co-operative engagement with a temple-bow, and having the other or head end portion of the member elongated and extending inward toward the other end of the holder, its wall being quite thin and resilient and concavo-convex in form cross-sectionally and adapted when in use to bear against and cover the outer or convex face of an elongated apertured ear or strap of a nose-piece, the said head part having a hole therethrough registering with that of the ear for receiving the usual holding screw.

2. In frameless spectacles, the combination with a nose-piece provided with a pair of laterally separated ears or straps adapted to receive a lens therebetween, of a bent connection member provided with an enlarged inner head portion having a degree of elasticity and adapted to be superimposed upon the outer surface of one of said ears, means for detachably securing it to the latter, and a temple-bow screw-jointed to the outer end of said connection.

3. In frameless spectacles, a nose-piece having a pair of laterally separated perforated ears, and a lens disposed therebetween,

in combination with a one-piece bent connection or temple-bow holder having a slightly convex or cup-shaped, spring-like head part constructed to receive and bear against 5 the outer or exterior face of one of said ears, a screw or fastening means passing transversely through said head, lens, and ear members for securing said parts together,

and a temple-bow jointed to the other or free end of the said bent holder.

In testimony whereof I have affixed my signature in presence of two witnesses.

JOSEPH SAVOIE.
